RADIO RECEIVER.

Ira O. Banks, Higginsville, Mo.

Application October 24, 1936, Serial No. 107,487

4 Claims. (Cl. 250—20)

This invention relates to signal volume control devices for radio receivers, and the primary object of the same is to improve the regulation characteristics of devices of this type.

Another object is to improve apparatus such as that disclosed in my Patent No. 2,047,092, for Radio antenna, issued July 7, 1936, wherein the effective tone volume of the radio receiver may be controlled by a pair of switches, one to ground either side of the input circuit with or without an outside antenna and the other to adjust the grounding by potentiometer means connected across said input circuit.

The foregoing and other objects and advantages will become apparent in view of the following description taken in conjunction with the drawing, wherein—

Figure 1 is a fragmentary circuit diagram of an input circuit illustrating my improved control unit used as a signal input regulating means between an outside antenna and ground;

Figure 2 is a similar view but showing the unit coupled up with both an outside antenna and an auxiliary or indoor antenna;

Figure 3 is a further circuit diagram showing the unit connected between the signal input and power supply circuits of a radio receiver;

Figure 4 is an exterior fragmentary view of a portion of a panel board with the improved control unit installed thereon;

Figure 5 is an enlarged interior view of the lower portion of Figure 4;

Figure 6 is substantially central transverse sectional view of the unit.

Referring to the drawing in detail, in Figure 1 a conventional input circuit is shown and includes a coupling A of the air core transformer type having its primary 6 connected between the antenna 7 and ground 8 through a resistance and control device generally indicated at B and embodying the features of the present invention. The secondary 9 of the coupling is in multiple with a variable condenser 10 and may, for example, be connected between the ground and grid of a thermionic tube, not shown, forming part of the main radio circuit, also not shown herein since such showing is not essential to an understanding of the invention.

The structure of the control device B is shown more or less in detail in Figures 4, 5 and 6 and comprises a resistance 11 which is attached to an insulated backing or supporting plate 12. A rotatable sliding contact member 13 is provided and is mounted on the inner end of shaft 14, member 13 having as a part thereof a pair of arcuate

shaped arms 13a and 13b which terminate in contacts 15 and 16, the latter being arranged in predetermined spaced relation and moving in unison when member 13 is rotated. At its one end, the resistance 11 is connected to a terminal 17 which is shown in Figures 4 and 5 as being wired to the ground post 18 of the radio set, and at its opposite end said resistance is connected to terminal 19, which is wired to the antenna binding post 20. Shaft 14 is electrically connected to terminal 21 which is wired to the main or outdoor ground binding post 22.

Arms 13a and 13b have fixed thereon limit stops 23 and 24 which are adapted to contact an outwardly projecting contact member in the form of a pin 25 and limit the extreme positions of rotation or sliding contact of the contacts 15 and 16, such extreme positions being just short of actual contact with terminals 17 and 19.

A switch arm 26 is mounted on shaft 14 and is rotatable independently of the latter, said arm being provided with a contact head 26a, note dotted outline in Figure 4, adapted for selective engagement with terminals 17 and 19 through electrical contacts 27 and 28 or adjustment to a neutral position between the latter.

Shaft 14 has secured on the outer end thereof a knob 29 having an indicating arrow 30 on the face thereof.

In Figure 1 the improved control unit is shown used as a potentiometer for adjusting the resistance between the main antenna 7 and ground 9, switch 26 being moved in electrical contact with terminal 17, thereby grounding this terminal. Resistance 11 for this purpose would be very high.

In Figure 2 the terminal 17 of the unit is connected through coil 31 with an auxiliary aerial 32. This latter aerial may be an indoor aerial or pick-up device of any suitable type. Switch 26 is in neutral position in this instance so that both aerials 7 and 32 connect through resistance 11 and contact member 13 with ground 8.

In Fig. 3 the improved unit is shown installed between the signal input circuit 7 and power supply circuit 33 of a radio receiver. Switch 26 may be used to either ground the antenna circuit direct by connecting it with terminal 19, or may be connected to terminal 17 to utilize the full adjustable resistance afforded by the unit.

The results of the improved unit are more pronounced in circuits such as those illustrated in Figures 2 and 3 than in Figure 1, or where the resistance is adjusted directly across a single main aerial and the ground. Comparing the double contact switch member 13 with a single

point contact, it will be seen that with the latter type of contact, for the greater portion of the time there is no veniering or tapering-off action from the one half of the resistor 11, while with the spaced double contact member as disclosed herein, one half of the resistance is being shunted out while the other half is being gradually shunted in, and when the member 13 is rotated to either one of its extreme positions, or where either one of the stops 23 or 24 contact pin 25, one of the contact heads 15 or 16 will be at a point approximately dead center, or will have divided the length of resistor 11 into two substantially equal parts. For example, where an auxiliary aerial 15 is used in conjunction with the main aerial as in Figure 2 and assuming that the member 13 is being rotated counterclockwise, the resistance in the main aerial line will be gradually increased while that in the auxiliary aerial line will be 20 gradually reduced. By adjusting the resistance at a certain point, the signals may be finely adjusted in accordance with the characteristics of the particular set in which the device may be installed.

25 Regardless of the theory of operation of the improved control unit, I have found from practical experience that improved results are obtained with the two point spaced contact over the conventional single point contact type of control unit.

30 Another feature of importance is that the potentiometer resistance in devices of this kind is seldom uniform throughout the length thereof, and with the spaced two point contact type of unit as shown herein, the particular resistance used may be correlated with the particular circuit with which it may be installed. Thus one circuit, or the aerial circuit for example, may be adjusted on one side of the resistance while the grid-biasing 35 40 resistance on the ground side of the circuit, for example, may be adjusted on the other side of the resistor.

A further point of advantage is that the two point switch arrangement is combined in one 45 unit and therefore costs less to manufacture. Practical experience has also shown that the device has longer life than the conventional single point contact.

50 The stops 23 and 24 on the arms 13a and 13b of the rotatable contact plate or member 13 are preferably adjusted so that when either one contacts with the projection 25, the other contact will be at a point of dead center or will divide the resistance in two substantially equal parts, as 55 heretofore noted. It is also preferred to adjust these stops so that when they contact pin 25 there will be a slight space between the contact head and its adjacent terminal, so there will be sufficient resistance left as not to pass a current 60 of any appreciable value as might occur should either contact 15 or 16 directly engage either terminal 17 or 19. Thus in operation, the contacts 15 and 16 at no time directly ground either terminal of the resistance. The switch 26 may be 65 used to selectively and directly ground either terminal 17 or 19 as shown in Figure 1, or said switch may be adjusted to a neutral position as shown in Figures 2 and 3.

It will be understood that the contacts 15 and 16 may be either the wiping or roller type and that certain other changes in design and arrangement of the parts of the improved unit may be adopted within the scope of the invention as 5 defined by the appended claims.

I claim:

1. In a radio receiver having a signal input circuit, a power supply circuit and a common return such as a ground for said circuits, a resistance unit comprising a single unbroken resistance having opposed terminals connected respectively to said signal input circuit and said power supply circuit and a movably mounted contact member connected to said common return, said contact 15 member having thereon a pair of contacts engaging said resistance and spaced a predetermined distance apart so as to always render ineffective a section of the resistance therebetween, the contacts being positively connected for movement in 20 unison.

2. In a radio receiver having a signal input circuit, a power supply circuit and a common return such as a ground for said circuits, a resistance unit comprising a single unbroken resistance having opposed terminals connected respectively to said signal input circuit and said power supply circuit and a pivotally mounted rotatable contact member connected to said common return, the contact member having contacts engaging said 25 resistance and positively connected for movement in unison therealong, the contacts being spaced to render ineffective a portion of said resistance therebetween.

3. In a radio receiver having a signal input circuit, a power supply circuit and a common return such as a ground for such circuits, a resistance unit having a single unbroken resistance with opposed terminals connected respectively to said signal input circuit and said power supply 40 circuit and an arcuate pivotally mounted rotatable contact plate connected to said common return, the contact plate having thereon contacts engaging said resistance and connected for positive movement in unison therealong, the spacing 45 of said contacts being such as to render ineffective substantially one-third of the resistance therebetween.

4. In a radio receiver having a signal input circuit, a power supply circuit and a common ground for said circuits, a resistance unit having opposed terminals connected respectively to said signal input circuit and said power supply circuit and a contact member connected to said ground and having thereon a pair of contacts engaging 50 said resistance and spaced from each other so as to always render ineffective a portion of the resistance therebetween, the contacts being positively connected for movement in unison to vary the positions of contact with said resistance 55 within certain limits, and a movable grounding switch to be selectively connected with either terminal of said resistance or disconnected therefrom.
